EMBLEM

Gene Mathias, Fort Worth, Tex., assignor to Plaques International Inc., doing business as P. I. Associates, and May Advertising Company, Inc., Fort Worth, Tex., fractional part interest to each

Filed May 15, 1972, Ser. No. 253,690

Term of patent 14 years

Int. Cl. D11—03

U.S. Cl. D29—11 F

The figure is a front elevational view of an emblem showing my new design. The back is plain and unornamented and the emblem is a flat sheet of no appreciable thickness.

I claim:

The ornamental design for an emblem, as shown and described.
